T. Peaseall,

Tubular Flour Cask.

No 11,200.

Patented June 27, 1854

Fig. 2.

UNITED STATES PATENT OFFICE.

THOMAS PEARSALL, OF SMITHBORO, NEW YORK.

VENTILATED FLOUR-BARREL.

Specification of Letters Patent No. 11,200, dated June 27, 1854.

To all whom it may concern:

Be it known that I, THOMAS PEARSALL, of Smithboro, in the county of Tioga and State of New York, have invented a new and useful Method of Preserving Flour, Meal, &c., and Preventing Such Commodities from Heating in the Cask; and I do hereby declare the following to be a full, clear, and exact description thereof, reference being 10 had to the accompanying drawing and to letters of reference marked thereon, and in which—

Figure 1 represents a flour barrel or cask; Fig. 2, a tube to be inserted longitudinally 15 in such cask.

It is well known to scientific as well as practical men that all commodities containing in themselves the constituents necessary to produce fermentation will, when closely 20 packed in bulk of sufficient size to prevent the air from penetrating them, sooner or later generate heat at the center, which gradually diffuses itself through the mass; hence the enormous quantity of flour and 25 meal, &c., spoiled in transportation and storing. It is also well known that decomposition invariably commences at the center of the bulk owing to the increased pressure there and to its being farther removed from 30 the refrigerating influence of the atmosphere. It is a common occurrence on opening a barrel of flour to find it perfectly sweet and good at top, bottom, and around the outside of the bulk, while at the center 35 it will be both hot and sour. While this is common in bulk of the size of a flour barrel it is rare in a half barrel; and I never saw or heard of a packed bulk of the size of a quarter barrel injuring in the smallest 40 degree from fermentation or decay in twenty five years practical experience. On this theory my invention is based and to remedy this evil I insert a tube or tubes longitudinally through the cask in which such 45 commodity is to be packed for the free circulation of air therethrough, so that the center of the cask is no longer the center of the

mass, and in proportion as you increase the diameter of the pipe you increase the number of centers in the bulk, thus mathematically dividing the mass into as many parts as required, which is equivalent to dividing the mass into as many smaller packages.

In the accompanying drawing (A) represents a flour barrel with holes (B') in each end in the center of the heads (A') to receive the tube (B), Fig. 2. In filling the cask the head (A') is taken out, and the tube (B) inserted in the hole in the lower head of the cask, the desired quantity of 60 flour or meal is packed therein and the upper head (A') is put into the cask again, the tube (B) protruding through the holes in each end of the cask, about half an inch, more or less, which is to be hammered down, 65 forming a flange on the heads. Thus the air can circulate freely through the center of the bulk and its liability to heat is entirely obviated, and at the same time the cask is materially strengthened. When 70 larger casks are used several tubes may be inserted in the same manner if found necessary. These tubes may be made of iron 75 tin wood or any other suitable material, porous, perforated, or otherwise.

What I claim as my invention and desire to secure by Letters Patent is—

The manner herein described of preventing fermentation of flour, meal, or other vegetable commodity by dividing the bulk 80 as specified, that is to say, by means of air pipes or passages arranged to run through the cask substantially as herein set forth, and whereby the flour is prevented from heating and becoming sour at the center of 85 the cask by the free circulation of the cold atmosphere or air through said tube.

In testimony whereof, I have hereunto 85 subscribed my name this first day of March, 1854.

THOS. PEARSALL.

Witnesses:

IRA REYNOLDS,
WM. M. SMITH.
